UNITED STATES PATENT OFFICE

118,051

DESIGN FOR A VALVE OR SIMILAR ARTICLE

Hamilton Merrill, Bridgeport, Conn., assignor to Manning, Maxwell & Moore, Incorporated, New York, N. Y., a corporation of New Jersey

Application August 16, 1939, Serial No. 86,733

Term of patent 7 years

To all whom it may concern:

Be it known that I, Hamilton Merrill, a citizen of the United States of America, residing at Bridgeport, in the county of Fairfield and State of Connecticut, have invented a new, original, and ornamental Design for a Valve or Similar Article, of which the following is a specification, reference being had to the accompanying drawing, forming a part thereof,

Fig. 1 is a top plan view of a valve showing my new design; and

Fig. 2 is a side elevation thereof.

I claim:

The ornamental design for a valve or similar article, substantially as shown.

HAMILTON MERRILL.
